UNITED STATES PATENT OFFICE.

SAMUEL KRAINER, OF CHICAGO, ILLINOIS.

HAT LINING.

Application filed May 15, 1922. Serial No. 560,879.

To all whom it may concern:

Be it known that I, SAMUEL KRAINER, a citizen of the United States, and a resident of the city of Chicago, in the county of Cook and State of Illinois, have invented certain new and useful Improvements in Hat Linings; and I do hereby declare that the following is a full, clear, and exact description of the same, reference being had to the accompanying drawings, and to the numerals of reference marked thereon, which form a part of this specification.

This invention relates to an adjustable inner lining for hats and the like, wherein an adjustable bandeau is provided to seat the hat properly on varying sizes and shapes of heads. Formerly it was a trade custom to furnish one size of hat for almost all requirements in the millinery field, and to depend upon the coiffure to fit the hat rather than the reverse condition. With bobbed hair, however, the customers naturally require a real fit, especially as hat pins are of no service in such circumstances.

I am aware that adjustable bands are not new in the art, but heretofore they have not been acceptable to the customers as they tended to hold the hat away from the forehead, thus emphasizing the fact that the hat was not a proper fit in the first place.

It is an object of this invention to provide a contractable sheath which will take up the slack at the back of the hat so that no indication of its presence is given by an unsightly gap between the wearer's forehead and the hat.

It is a further object of this invention to build the sheath or bandeau into the lining of the hat in such a way that casual inspection will not disclose its presence.

It is an important object of this invention to use a sheath made of a stiff cloth so cut as to be of a springy nature, as it has been found that such a sheath forms a better and more comfortable fit on the head than a soft sheath.

Other and further important objects of this invention will be apparent from the disclosures in the specification and the accompanying drawings.

My invention is shown (in a preferred form) in the accompanying drawings, wherein a woman's hat is used as an illustration. It will be apparent that this invention is equally applicable to men's hats and caps and is of especial utility with stiff hats,

which seldom make a perfect fit all around the wearer's head.

In the drawings:

Figure 1 is a plan view of a hat showing in dotted lines the shape assumed by the sheath or bandeau of my invention when the sheath is contracted.

Figure 2 is an elevation of the hat with part of the rim broken away.

Figure 3 is a section on the line 3—3 of Figure 1 with part of the lining broken away.

Figure 4 is a section similar to Figure 3 with slight modifications in the sheath or bandeau.

As shown on the drawings:

My invention is shown embodied in a hat consisting of a crown 1 and brim 2 which form no part of this invention and therefore the particular shape thereof is immaterial.

My invention consists of a sheath or bandeau 3 fastened at its lower edge to the junction of the hat crown 1 and brim 2 in the usual position for a sweat band in a man's hat. The sheath is composed of a folded piece of stiff cloth such as certain grades of muslin and is cut on the bias so as to form a stiff springy element. Through this folded sheath is threaded a tape or ribbon 4, the ends of which come out at the opening formed at the joint of the sheath, which may be located at one side or the rear of the hat. On a woman's hat an aperture 5 in the crown is provided in approximate alignment with the opening in the sheath and the ends of the ribbon or tape are brought through the aperture and allowed to dangle over the brim of the hat in the form of streamers. Of course, the tape within the sheath may be of one kind of material and the streamers formed of some ornamental fabric.

If desired, an inner lining 6 can be placed in the crown covering the sheath and secured to the hat by the same stitching that secures the sheath thereto.

As shown in Fig. 3, the tape is sewed into the sheath at 7 around the front part of the hat so that no movement therebetween is possible; therefore, all contraction of the sheath occurs in the rear part of the hat producing a form shown in the dotted lines of Fig. 1. It will be apparent that when the tape ends are brought out at one side of the hat, one end will be immovable be-

cause it is sewed into the sheath around the front part while the other end will be the one that contracts the rear portion of the sheath.

- 5 The modification shown in Fig. 4 uses two tapes fastened in the sheath, one on each side of the hat, and when using a side outlet one tape comes directly out while the other is threaded through the sheath around the 10 rear part of the hat. The action of this modification is identical with the other form, the purpose being to save some material. In this form the front part of the hat may be provided with a usual lining or sweat 15 band 3a.

In use the tapes are drawn up until the hat is a good fit and tied. Thereafter ordinarily no changes would be required, but simply untying the tapes would permit readjustment.

In case further elasticity is required after the tapes have been tied in adjusted position, said tape may be provided with one

or more elastic inserts which allow of a certain amount of yielding supplementing 25 the yielding of the sheath 3.

I am aware that numerous details of construction may be varied through a wide range without departing from the principles of this invention, and I therefore do not 30 purpose limiting the patent granted otherwise than necessitated by the prior art.

I claim as my invention:

In a hat, a sheath attached thereto at its lower edge, and a tape extending around the 35 upper free edge of said sheath and fastened to the portion thereof around the front of the hat, the ends of said tape extending through an aperture in the hat.

In testimony whereof I have hereunto 40 subscribed my name in the presence of two subscribing witnesses.

SAMUEL KRAINER.
